UNITED STATES PATENT OFFICE

JOSEPH JOHN STOETZEL, OF QUEENS VILLAGE, NEW YORK, ASSIGNOR TO G & G ATLAS SYSTEMS, INC., OF NEW YORK, N. Y., A CORPORATION OF NEW YORK

PNEUMATIC DISPATCH OUTLET VALVE

Application filed January 14, 1930. Serial No. 420,647.

The present invention relates to pneumatic dispatch service systems and has for an object to provide an improved delivery apparatus. This application is a continuation in part of my pending applications, Ser. No. 289,687, filed July 2, 1928, and Ser. No. 320,345, filed November 19, 1928.

The delivery of the carrier at high speed offers certain obvious objections such as the bouncing of the carrier at the delivery station and the noise of delivery. The present invention provides an improved arrangement whereby an air cushion is formed to retard the carrier as it approaches the point of delivery, the arrangement however being such as not to interfere with the actual delivery of the carrier when it reaches the delivery outlet. In the preferred embodiment to be more particularly described for the purposes of illustrating the principles of the invention, the operation is entirely automatic, the arrangement being such that the pressure built up in front of the moving carrier in the delivery end of the tube will not open the delivery door while the door is, nevertheless, left free to be opened by the carrier itself engaging the door. In the preferred embodiment also provision is made whereby the control valve is caused to be closed by the pressure built up in the delivery tube as the carrier approaches the point of delivery.

The nature and objects of the invention will be better understood from a description of a selected illustrative embodiment for the purposes of which description reference should be had to the accompanying drawings forming a part hereof and in which—

Figure 1 is a diagrammatic view of a pneumatic dispatch system showing an improved delivery apparatus embodying the present invention, and

Figure 2 is a detail sectional view of said delivery apparatus.

The arrangement shown for the purposes of illustration makes provision for retarding the carrier before delivery by causing an air cushion to be formed in the delivery tube ahead of the carrier, the delivery valve being held closed against the air cushion pressure until the carrier engages said valve where-

upon it may be freely opened to permit discharge of the carrier. As shown, the lower end of a vertical carrier tube 5 where the carrier would ordinarily be discharged at particularly high velocity is provided with a delivery valve 6 pivoted at 7 in the casing 8 and having a pressure balancing vane 9 which is as nearly as possible of the same area as the main valve. The area of the balancing vane 9 may be slightly greater than that of the vane 6 if the weight is not sufficient to hold the valve closed during operation. The vane 9 is weighted as indicated at 9' to insure closing of the valve but the weight is too light to interfere with the opening of the valve by the weight of the carrier. As the carrier 10 passes the air suction connection 11 and approaches the delivery valve, the air ahead of the carrier will be confined to form an air cushion effective to retard the carrier so that it approaches the valve with negligible velocity. The two part valve is automatically held closed because the pressure of air causes a force against the area of the vane 9 which tends to hold the valve closed and which is equal to the force against the vane 6, but as the carrier actually engages the valve or an upstanding fin 12 formed thereon, the weight of the carrier will be sufficient to open said valve.

The arrangement described has been developed more particularly for use with vacuum dispatch systems. A control valve of the type commonly used in said systems is shown at 15. It is desirable that this control valve be closed as the carrier approaches the delivery valve and to this end provision is made for causing the air pressure in the delivery tube to actuate said valve. In the arrangement shown the valve casing 8 is connected by a tube 16 and a small connecting tube 17 to the chamber 18 of the control valve whereby the control valve will be closed directly by the pressure of the air cushion. Preferably also an auxiliary valve 20 is arranged to close the suction tube 21 between the control valve and the main dispatch tube 5. The valve 20 is pivoted at 22 in valve casing 23 in such a position that the pressure in the tube 16 will cause a closing of said valve. The

valve 20 is of L-shape with a smaller area subject to pressure in the main tube and a larger area subject to pressure in the tube 16 as clearly shown in Fig. 2. The closing of the valve 20 would tend to cause a vacuum and effect an opening of the control valve 15 but this will be overcome by the admission of air to the chamber 18 as above explained.

10 The foregoing description of a particular embodiment is illustrative merely and is not intended as defining the limits of the invention.

I claim:—

15 1. In a pneumatic dispatch system, the combination with a pneumatic dispatch tube of a delivery valve arranged to be opened by the engagement of the carrier thereagainst and means responsive to the pressure of air ahead of an approaching carrier for holding 20 said valve closed, said means being inoperative to cause opening of the valve when the pressure in the line is sub-atmospheric.

25 2. In a pneumatic dispatch system, a two-part delivery valve, one part being arranged to open to permit discharge of a carrier, the other part responding to pressure of air ahead of the carrier to hold the first part closed against said pressure.

30 3. In a pneumatic dispatch system, a two-part delivery valve, one part being arranged to open to permit discharge of a carrier, the other part responding to pressure of air ahead of the carrier to hold the first part closed against said pressure, and means to hold said valve closed when there is suction 35 in the line.

40 4. In a pneumatic dispatch system, the combination with a carrier delivery tube and a suction tube entering laterally thereof of a valve in said suction tube actuated by the pressure of air ahead of the carrier in the delivery unit for closing said suction tube while leaving the delivery tube open for the passage of the carrier.

45 5. In a pneumatic dispatch tube system, the combination with a delivery tube of a delivery valve normally closing said tube having oppositely acting balanced pressure areas whereby increase or decrease of pressure in the delivery tube will not open the valve.

55 6. In a pneumatic dispatch tube system, the combination with a delivery tube of a two-vane pivoted valve normally closing said tube, the vanes being of substantially equal areas whereby neither pressure or suction within the tube will open the valve, said valve being arranged to be opened by the weight of the carrier thereagainst.

60 7. In a pneumatic dispatch system, the combination with a dispatch tube, a carrier delivery unit and a control valve controlling the suction in the dispatch tube and having a pressure responsive diaphragm chamber, 65 of a connection between the delivery unit

and the diaphragm chamber arranged to admit air from the delivery unit to said chamber to cause a closing of the control valve when the air pressure is built up in the delivery unit ahead of an approaching carrier. 70

8. In a pneumatic tube dispatch system, the combination with a discharge tube for delivery of a carrier substantially fitting said tube of a valve normally closing said tube 75 but positioned to be moved aside by the pressure of the carrier there against and means responsive to air pressure in the tube tending to hold said valve in closed position against the action of the air pressure in the tube tending to open the valve thus retarding the passage of the carrier, substantially as described. 80

9. In a pneumatic dispatch system, the combination with a carrier delivery unit comprising a delivery tube and a separate suction tube of a valve actuated by the pressure of air ahead of the carrier in the delivery unit for closing said suction tube. 85

10. In a pneumatic tube dispatch system, 90 the combination with a discharge tube for delivery of a carrier substantially fitting said tube of a valve in the tube arranged to be held closed automatically by the change of air pressure, which movement of a carrier causes 95 in said tube, to obstruct the flow of air and thereby to impede the movement of the carrier as it approaches the point of delivery, substantially as described.

11. In a pneumatic tube dispatch system, 100 the combination with a discharge tube for delivery of a carrier substantially fitting said tube of means for checking the movement of a carrier as it approaches the point of delivery comprising a valve having larger and 105 smaller areas exposed to pressure of the air within the tube, the arrangement being such that the pressure on the larger area tends to close the valve and the pressure on the smaller area tends to open the valve, substantially 110 as described.

12. A pneumatic tube discharge section as defined in the preceding claim in which the portion of the valve presenting the smaller area obstructs the discharge tube and is arranged to be moved from obstructing position by pressure of the carrier thereagainst, substantially as described. 115

13. In a pneumatic tube dispatch system, 120 the combination with a discharge tube for delivery of a carrier substantially fitting said tube of a pivoted valve having on one side of the pivot a portion of smaller area disposed transversely of the tube and arranged to be moved aside by the carrier engaging therewith and on the other side of the pivot a portion of larger area exposed to the pressure within the tube and so arranged that the air pressure within the tube when effective against both areas tends to hold the valve 125 130

in closed position thereby retarding the passage of the carrier, substantially as described.

14. A pneumatic tube line comprising a discharge tube section for delivery of a carrier substantially fitting said tube and a valve closing said discharge tube to provide a compression chamber for retarding the carrier comprising a pivoted valve member having on one side of the pivot a portion of smaller area disposed transversely of the tube and arranged to be moved aside by the carrier engaging therewith and on the other side of the pivot a portion of larger area exposed to the pressure within the tube and so arranged that the air pressure within the tube when effective against both areas tends to hold the valve in closed position, substantially as described.

15. In testimony whereof, I have signed my name to this specification this 8th day of January, 1930.

JOSEPH JOHN STOETZEL.
